ATTORNEY

UNITED STATES PATENT OFFICE.

JACOB M. UMBERGER AND VERN S. PERRINE, OF MONUMENT, ILLINOIS.

FASTENER FOR THE LIDS OF MILK OR CREAM CANS.

Application filed September 8, 1927. Serial No. 217,396.

This invention relates to certain novel improvements in fasteners for the lids of milk or cream cans and has for its principal object the provision of an improved construction of 5 this character which will be highly efficient in use and economical in manufacture.

Prior to our invention it was customary to depend upon the frictional fit between the neck of a milk or cream can and the lid there- 10 of for holding the lid in place upon the neck. In shipping milk or cream cans it has been found that the lid in many instances works loose and due to vibration the contents of the cans is splashed around and finds exit through 15 the neck around that part of the lid inserted therein. It is therefore one of the many ob- jects of this invention to provide a simple and inexpensive fastener for holding the lid in position upon the neck and which fastener 20 may be expeditiously placed in and taken from fastening position.

A still further object of the invention is to provide a fastener which includes an ele- 25 ment yieldably acting upon the lid for hold- ing the lid in proper position with respect to the neck of a milk or cream can or the like.

Other objects will appear hereinafter.

The invention consists in the novel combi- 30 nation and arrangements of parts to be here- inafter described and claimed.

The invention will be best understood by reference to the accompanying drawings, showing the preferred form of construction and in which:

35 The single figure is a part sectional detail view of a can and lid showing the invention in position.

In constructing our invention we have en- 40 deavored to provide a fastener of the charac- ter hereinafter more fully described which is adaptable to milk and cream cans of various sizes, and shapes and in the present instance we have shown in the accompanying drawing a conventional can 9 which includes a neck 45 10. This neck 10 has a mouth 11 which is of a frustro-conical shape. A lid is indicated at 12 and this lid is adapted to close the neck of the can. The lid has an angular flange 13 at its bottom portion and this flange is adapt- 50 ed to fit in the neck 10. The upper portion of the lid is likewise frustro-conical in shape to conform with the shape of the mouth 11. The lid 12 is provided with a handle 14 which facilitates removing the lid from closing 55 position. The can also is provided with

handles 15 to facilitate moving the can about. In the present instance the peripheral edge 16 of the lid is partly rolled and this edge portion rests upon the bead 17 of the mouth.

The above description is an outline of one style of can with which our invention can be associated. In the present and preferred form of a construction it has been found ad- 60 visable to associate with each can two fas- teners and the description to follow will re- late to one fastener but it is understood that the description is equally applicable to the other fastener.

Our improved fastener includes a clip 18 which is secured to the neck 10 by suitable 70 connecting elements 19 such as rivets or the like. To this clip is connected one end por- tion 20 of a spring 21. A hook is indicated at 22 and this hook is substantially of a zig- 75 zag construction whereby to provide two U- shaped portions 23 and 24 respectively either of which are adapted to engage the edge 16 of the lid. The end portion 25 of the hook is connected as at 26 to the end portion 27 of the spring 21.

In use when the spring and hook is con- 80 nected to the can by means of the clip 18 and rivets 19, the lid is fastened in position by dis- posing one of the U-shaped portions in en- gagement with the edge 16. In this position the spring 21 will yieldably hold the hook in lid fastening position. The outer U- 85 shaped portion 24, when the U-shaped portion 23 is utilized for holding the lid, may be used as a finger piece whereby to expedi- 90 tiously detach the hook from lid holding po- sition.

We have shown in the accompanying 95 drawing a clip for connecting the end por- tion 25 of the spring to the can and it is pointed out if desired, the clip may be dis- pensed with and the end portion of the spring connected directly to the can by means of the rivet 19 or by means of a suitable nut bearing bolt of a well known construction.

While we have illustrated and described the preferred form of construction for carry- 100 ing our invention into effect, this is capable of variation and modification, without de- parting from the spirit of the invention. We, therefore, do not wish to be limited to the precise details of construction set forth, but desire to avail ourselves of such variation and modification as come within the scope of the appended claims.

Having thus described our invention what we claim as new and desire to protect by Letters Patent is:

1. A fastening device for the lid of a can including a hook element providing U-shaped portions either of which being adapted to engage the edge of the lid and one of said portions being adapted to serve as a finger piece, a spring member having one end 10 portion connected to the hook element for yieldably bearing the edge of the lid against the edge of the mouth of the can, and means for connecting the opposite end portion of the spring member to the body of the can.
- 15 2. A device of the class described including a fastening element having a substantially U-shaped portion provided therein intermediate the ends thereof, one of the ends of said element being arranged to provide a

loop portion adapted to be disposed at one of the ends of said U-shaped portion, the other of said ends being arranged to provide another U-shaped portion adapted to open in the same direction as said first named U-shaped portion and adapted to be connected to the other of said arms whereby to define a U-shaped portion therebetween, a clip element adapted to be secured to a can, and a spring member adapted to be extended between said clip member and said loop on said fastening element whereby said intermediate U-shaped portion may be urged to hold a lid in closing position with respect to the outlet of said can.

In testimony whereof we affix our signatures.

JACOB M. UMBERGER.
VERN S. PERRINE.
